CABINET FOR ELECTRONIC EQUIPMENT
OR SIMILAR ARTICLEDouglas Warner, Berkeley, Calif., assignor to James B.
Lansing Sound, Inc., Los Angeles, Calif.

Filed Mar. 7, 1973, Ser. No. 338,748

Term of patent 14 years

Int. Cl. D14—01

U.S. Cl. D26—14 G

FIG. 1.

FIG. 2.

FIG. 4.

FIG. 3.

FIG. 5.

FIG. 1 is a front perspective of a cabinet for electronic equipment or similar article embodying my new design with the front covered by a grille;

FIG. 2 is a top plan thereof, the bottom being identical;

FIG. 3 is a side elevation thereof, the opposite side being identical;

FIG. 4 is a rear elevation thereof; and

FIG. 5 is a front perspective thereof with the grille member omitted.

I claim:

The ornamental design for a cabinet for electronic equipment or similar article, substantially as shown and described.
